Oscar Geier

UNITED STATES PATENT OFFICE.

CHARLES LAVIE, OF NEW YORK, N. Y.

MARCEL WAVER.

1,217,610.

Specification of Letters Patent. Patented Feb. 27, 1917.

Application filed August 11, 1916. Serial No. 114,349.

To all whom it may concern:

Be it known that I, CHARLES LAVIE, a citizen of the Republic of France, and a resident of New York, in the county of New York and State of New York, have invented new and useful Improvements in Marcel Wavers, of which the following is a specification.

This invention relates to improvements in implements for improving the appearance of women's hair and relates to that type of apparatus used in producing the so-called "Marcel wave."

The principal object of the invention is to provide a light, easily operated implement upon which the hair may be intertwined, the same being afterward so treated that the undulations imparted to the hair are given permanency.

A further object is to provide such implements in forms whereby a plurality of locks of hair may be operated upon simultaneously and without confliction one with the other.

These and other objects are attained by the novel design and construction hereafter described and shown in the accompanying drawing, forming a material part of this disclosure, and in which:—

Figure 1 is a perspective view illustrating the application of the invention.

Fig. 2 is a perspective view showing the implement in detail.

Fig. 3 is a similar perspective view indicating the manner in which the hair is entwined upon the instrument.

Fig. 4 is a partial plan taken on line 4—4 of Fig. 2.

Fig. 5 is a transverse sectional view taken on line 5—5 of Fig. 2.

Fig. 6 is a similar transverse sectional view taken on line 6—6 of Fig. 2.

Fig. 7 is a transverse view of one of the prongs taken on line 7—7 of Fig. 2 and

Fig. 8 is a cross sectional view taken on line 8—8 of Fig. 2.

The implement consists essentially of a light metal instrument, preferably of aluminum, having a central sinuous web 10 formed with a handle 11, the latter having concave narrow side edges 12 and terminating in a widened element 14, the outer edge 15 of which is finished concavely.

At the front of the instrument a tooth or prong 16 is formed, the same having a flattened inner edge 17 and joined to the center web 10, while directly opposite to the prong 16, is a similar but longer prong 18.

A plurality of like prongs 18' and 20' are formed at regularly spaced intervals extending from the central web 10, alternating with spaces 19 and 21, directly opposite.

The cross section of the web or rib 10, best shown in Fig. 6, will be seen to be oval or elliptical; the prongs 18' and 20' are of cylindrical cross section, tapering slightly outward at their extremities, forming in effect inverted cones about which the hair is disposed as clearly shown in Fig. 3.

In operation, a lock, tuft, or tress of hair, close to the scalp, is secured to the prong 16, by a cord passed through the slot 25, woven about the first prong 18, curved over the central rib 10, coiled once about the first succeeding prong 20', returned to the opposite side of the second prong, and so continued until the handle is reached, any excess length being turned over the extreme end 15 and secured by a band 23, a similar fastening being used to tie the hair close to the scalp, the fastening passing through the slot 25, in the prong 16.

When the several locks of hair are engaged with the prongs, the hair is moistened with a certain solution and incased in a paper tube 28, adapted to be inserted in an electrical heater 29, connected by wires 30 with some source of electric energy.

The hair is subjected to a moderately high temperature for a short period, as from ten to fifteen minutes, whereupon the heater is removed, the tube withdrawn and the hair loosened from the implement, it then having acquired a particular wavy condition known as the "Marcel wave" and will remain in such condition irrespective of washing, shampooing, or other treatment, including brushing and combing, for a period of several months without becoming straight.

As all the edges of the instrument are smoothly rounded and no sharp bend given the hair the implement may be used with entire safety, and without detriment to the hair or scalp.

Having thus described my invention, together with the manner of its construction, application and use what I claim as new and desire to secure by Letters Patent, is:—

1. In an implement of the class described, the combination with a handle having its side and rear edges formed concavely, of a thin sinuous web having an elliptical cross section formed with said handle, and a plurality of inverted conical projections extend-

ing from said web upon opposite sides, uniformly spaced and so disposed that the projections on one side are directly opposite the spaces between the projections on the other 5 side.

2. In an implement of the class described, the combination with a flat handle having a concavely formed rear end, a thin sinuous web extending from said handle, inverted 10 conical projections extending oppositely

from said web alternating with the spaces between said projections, and a projection of lesser length formed directly opposite the outermost projection on the rib, said short projection having an enlarged head slotted 15 longitudinally and adapted to have hair strands secured therein.

In testimony whereof I have signed my name to this specification.

CHARLES LAVIE.
